DEPOSIT RECEPACLE

Charles F. Meilink, Toledo, Ohio

Application May 3, 1934, Serial No. 723,651

4 Claims. (Cl. 70—50)

This invention relates to protective chambers, especially for valuables.

This invention has utility when incorporated in cash drawers with features for and against release thereof.

Referring to the drawings:

Fig. 1 is a front view, with parts broken away, of an embodiment of the invention as a pedestal for a cash register or as a desk to be located on top of a counter or support;

Fig. 2 is a fragmentary view from the right of the device of Fig. 1;

Fig. 3 is a fragmentary view showing a mounting for the housing as depending from a deck or 15 under-side of a counter;

Fig. 4 is a detail view showing the mounting as for on a counter;

Fig. 5 is a section on the line V—V, Fig. 1;

Fig. 6 is a detail view from within looking at 20 the lock and re-locker for the closure below the drawer;

Fig. 7 is a section on the line VII—VII, Fig. 5;

Fig. 8 is a section on the line VIII—VIII, Fig. 7;

Fig. 9 is a wiring diagram of the disclosure 25 herein for alternating current; and

Fig. 10 is a wiring diagram of the controls hereunder as adapted for direct current.

Counter 1 may have upwardly therethrough bolts 2 with nuts 3 thereon effective in engaging 30 bottom 4 of housing having rear wall 5, side walls 6, 7, and top or deck 8. This housing is shown with front 9 having upper opening 10 and lower opening 11. In this upper opening 10 is drawer having front 12. Adjacent this front opening 10

35 the housing is provided with channels 13 weld anchored with the weld assembled housing. These channels 13 have mounted thereon upper rollers 14 and lower pair of rollers 15 effective to embrace rails 16 upon opposite sides of drawer

40 17, extending from the drawer front 12. This drawer is shown as provided with coin compartments 18 in the forward portion, miscellaneous receptacle 19, and bill receptacles 20 rearward from the coin receptacles 18. These bill recep-

45 tacles may have weights 21 mounted by links 22 effective to hold the paper money against shifting upward as the drawer is thrust outward. This drawer 17 has rear wall 23 mounting clip 24 in holding compression spring 25 in register with

50 socket 26 fixed by bracket 27 with the rear wall 5 of the housing. This spring 25 is normally effective as a kick out for thrusting the drawer into opening position. The rails 16 extend rearwardly to abut the rear wall 5 in bringing the

55 drawer front 12 into proper position in the open-

ing 10. At the outward thrust of the drawer depending lug 28 (Fig. 7) strikes lug 29 fixed with the housing precluding thrusting of the drawer clear of the case or housing. If it be desired to remove the drawer from the housing, slight elevation of the front 12, as permitted by the rearwardly spaced roller 14, clears the lugs 28, 29, and full removal may be had.

In the housing or case below the drawer is located partition 30 spaced by horizontal portion 10 31 from the rear wall 5, thus providing a supplemental forward compartment 32 below the drawer, which forward compartment has at the opening 11 closure plate 33. This closure plate 33 has key locks 34, 35, so that as keys may be 15 separately held say by a proprietor or auditor and the attendant or clerk, each must be present to effect authorized opening of this compartment 32. There is one key for the lock 34 and another key for the lock 35. As both keys are used there 20 may be retraction of bolt 36 (Figs. 6, 7). This bolt 36 is in engaging position at reinforcement 37 adjacent the lug 29. This bolt 36 and the locking mechanism from the locks 34, 35, has plate 38 shiftable at unauthorized attack. In the in- 25 stance anyone should attempt to force the locks 34, 35, such forcing would cause the plate 38 to have its lug 39 shift clear of cross bar 40 anchored with bolts 41, each as normally urged upward by compression helical springs 42, anchored with the respective bolts and engaging against brackets 43 fixed with the closure plate 33. With this lug thus clear of the cross bar 40, the pair of bolts 41 move into locking position in the opening 11 at the upper side of this plate 35 or front 33, with lugs 44 at the lower side of the plate 33 engaging the reinforcement 45 in the housing or casing. This is an additional locking device having the bolts 41 supplementing the locker having the bolt means 36. Authorized 40 opening of this compartment 32 by removal of the closure 33 gives access to re-set switch 46 on shield 47.

Behind this shield 47 is the set of protective electric devices. The drawer 17 has bottom 48 45 in the central portion provided with depending lugs 49 mounting therebetween roller 50, normally engaged by catch 51 (Fig. 8).

This catch 51 is normally upwardly thrust into engaging position by helical spring 52 coacting 50 with collar 53 and abutting bracket 54 serving as a guide for this bolt 51. This bracket 54 is weld mounted on the partition 30. Bolts 55 mount bracket 56 carrying resistance 57 having core 58 connected by link 59 to the bolt 51. As this 55

resistance 57 is energized, the bolt 51 is retracted against the resistance of the spring 52, thereby allowing the spring means 25 to become effective and shift the drawer into opening position.

5 As the drawer is thrust back toward closing position, beveled side 60 of this bolt 51 rides on the roller 50 to retract the bolt against the action of the spring 52 and allow the drawer to be closed with a self-latching action for this bolt or latch 10 as the drawer is in fully closed position. A bracket 30' at one side of the solenoid device 57, 58, and in the compartment 32 has bolts 61 mounting bracket 62 carrying supply current device transformer 63. In the compartment 32 at the opposite side of the bolt withdrawing solenoid, bracket 64 mounts solenoids 65, 66, having respective cores or plungers 67, 68, interconnected by rocker 69 and acted upon by spring 70 as a holder resistance in effecting snap throw as passing 15 mid or neutral position. The core or plunger 67 carries insulation block means 71 having compression springs 72 thereon to locate crosswise contacts 73, 74, 75, 76. It is thus seen that as the plunger 67 is drawn into the coil 65, by energizing such coil there is upward throw to close the switches 73, 75, 76 (Fig. 9), and open the switch 74. Energizing of the coil 66 effects a reverse snap throw in closing the switch 74 and opening the switches 73, 75, 76. There is thus a 20 solenoid double throw switch device as located in the compartment 32.

The one whose duty is to have authorized access to this drawer may depress push button 77 (Fig. 5) effecting energizing of the resistance 57, thus 25 retracting the bolt so the drawer snaps out of the casing or housing. In the event push button 78 adjacent the push button 77 be the one which is pushed or operated, it is not possible thereafter to operate the bolt or latch 51 from the resistance 57 without access to the re-setting device button 46, which is inaccessible due to the closure 33 serving as a hindrance against unauthorized re-setting. Pushing of this button 30 78 is effective as an alarm signal as well as this safety signal against drawer release, and the same end may be served by remote control, say at floor push button or switch 79 (Fig. 1). These push buttons 77, 78, are at the side 7 of the case or housing. At the side 6 of this case or housing, there is connection fitting 80 (Fig. 2) for power 35 supply current, connection fitting 81 for alarm outlet as say for district signal service such as A. D. T. There is fitting 82, say for conduit 83 extending to the foot switch or remote signal 40 79. Fitting 84 may be to other alarm signals or remote control devices analogous to that of the foot switch 79, which may be either hand, foot or otherwise controlled.

Power supply lines 85, 86, (Fig. 9) go to the 45 bracket 62, and as lower or different voltage for the current may be required from that of the power lines, which current may be taken as 110 volt, 60 cycle. The transformer 63 may be mounted at the bracket 62. In the event it be desired to take line voltage, there may be branch 50 88 from the line 85 to switch 75, thence by line 89 to the switch 77, thence by line 90 to the resistance 57 and by line 91 to the line 86. From the transformer 63 line 92 extends to the coils 66, 65.

From the coil 66 extends line 93 to the switch 73, and from such switch 73 extends line 94 to the switch 78. From the switch 78 extends line 95 to the bracket 62 and thence by line 96 back to the transformer 63. This means that with the

switch 73 closed, a closing of the switch 78 energizes the coil 66 and throws the switch 73 into open position, precluding energizing of the resistance 57 were one to push the switch 77. From the coil 65 extends line 97 to the switch 74 and from thence extends line 98 to the switch 46. From this switch 46 extends line 99 to block 62, where circuit is completed by line 96 back to the transformer 63. It is thus possible to re-set the switch 73 into closed position only by accessibility 10 to the compartment 32 by removal of the closure 33 and authorized operation of the switch 46. The operation of the switch 78 which effected the opening of the switch 73 opened the switches 75, 76. Opening of the switch 76 breaks the 15 circuit between the lines 100, 101, which pass the block 62 to remote alarm 102 as independently energized. It is thus clear that the disturbance other than operation by the authorized attendant, is automatically effective for a remote 20 alarm.

The line 94 as extending to the switch 78 has branch 103 extending to the bracket 62. From this bracket 62, the line 103 has branch 104 which may extend to floor switch 79 with line 105 therefrom back to the bracket 62 for connection by line 96 to the transformer 63 in completing the circuit. Thus the switch 79 may be effective as the switch 78 for opening the switch 73 by energizing the coil 66. Also connected to the line 30 103 at the bracket 62, in addition to the line 104, is line 106 extending to remote switches 107, say about the store or place of business where other attendants may use such in emergency, as in the event of a raid or robbery. 35

From these switches 107, return lines 108 may extend for connection by the line 96 back to the transformer 63. It is thus seen that the switches 78, 79, 107, may be similarly effective for this 40 emergency safeguard.

In the event it is desired to use direct current instead of alternating, there may be supply lines 109, 110 (Fig. 10). Instead of the disconnecting or protective switches being on a lower voltage than the supply current, such may be connected 45 in at supply current voltage by cross-over 111 at the bracket 62. From the supply lines 110, 109, line 92 extends directly to the two-way solenoid switch device having the coils 65, 66. The line 110 has therefrom line 112 past switch 113 to the 50 resistance 57. By-passing this switch 113 is resistance 114 effecting voltage drop for the resistance 57. The resistance 114 opens the switch 113 as the circuit is closed for the resistance 57, thereby avoiding heating hazard at such coil and 55 effectively holding down the voltage therefor. It is thus seen that the switch 113 passes current directly from the line 112 to the resistance 57 while the circuit to the resistance 57 is completed by closing switch 77. Upon closing switch 60 77, the resistance 57 is energized and with constant use there is a tendency for the resistance 57 to heat. In D. C. operations, to avoid any possibility of overheating, the resistance 114 is placed in series with the bolt operating resistance 57. 65 The resistance 114, as a solenoid, opens the switch 113 simultaneously with the energizing of the resistance 57 so that immediately there is force enough created for the resistance 57 to operate the bolt 51 and the switch 113 opens so that current flow through the resistance 57 is also through the resistance 114, thereby reducing the tendency of the resistance 57 to overheat. 70

In the operation hereunder, there is provided a casing or housing as a protective structure here- 75

in shown as including a cash drawer, self-opening upon release. There is protection against such release in the matter of the latch 51 to be electrically withdrawn by the operation of the 5 coil 57. Any cut-off of supply current precludes release of the latch for opening the drawer. There is authorized release by depression of button 77, while supplemental thereto unauthorized or robbery motive is forestalled by operation of 10 any of the switches 78, 79, 107. It is further important to note that this unauthorized or hazard safeguard brings about a precluding of even authorized access due to the hindrance requiring re-setting. This re-set is electrical. The coil 15 65 is a setting for authorized control. Coil 66 is a setting against the authorized or unauthorized control.

With the hindrance introduced such is requirement for re-set necessitating the holders of 20 the keys for the respective locks 34, 35, jointly to effect withdrawal of the bolt 36 so that the panel or closure 33 may be moved from the opening 11 to permit operation of the re-setting switch 46, thus to energize the coil 66. In the event the 25 burglarizing should include attack upon this closure 33 any shifting of the locker involving the devices 34, 35, effects re-locker operation at the bolts 41 enhancing the protective value by introducing this additional hindrance against attack. 30 As the re-set switch 46 is operated, the installation is in set-up for normal functioning by the authorized one depressing the button 77. It is to be noted that the emergency or danger operations, if effective in any one of the switches 35 78, 79, 107, not only cuts out the authorized and unauthorized access to the repository drawer 17 for keeping such in the casing or protective housing, but that there is the remote signal to the alarms 102 by the lines 100, 101. These are effective at cessation of current flow.

What is claimed and it is desired to secure by Letters Patent is:

1. A protective receptacle including a fixed housing and an openable member, a bolt for pre-

benting the opening of the member, a solenoid for withdrawing said bolt to release the member for opening movement, a circuit for said solenoid including a switch, opening and closing solenoids for opening and closing the switch, the first 5 named solenoid being operable only when the switch is closed.

2. A protective receptacle including a fixed housing and an openable member, a bolt for preventing the opening of the member, a solenoid 10 for withdrawing said bolt to release the member for opening movement, a circuit for said solenoid including a switch, opening and closing solenoids for opening and closing the switch, and switch means movable in one direction for operating an 15 opening solenoid and in the opposite direction for operating a closing solenoid, the first named solenoid being operable only when the switch is closed.

3. A protective receptacle including a fixed 20 housing and an openable member, a bolt for preventing the opening of said member, a solenoid for withdrawing said bolt to release the member for opening movement, a circuit for said solenoid including a switch, opening and closing 25 solenoids for opening and closing the switch, and manually controlled means for resetting the switch, whereby the switch is rendered effective for protective control of the openable member through the bolt, the first named solenoid being 30 operable only when the switch is closed.

4. A protective receptacle including a fixed housing and an openable member, holding means for preventing the opening of the member, a protective control device for the holding means 35 in the housing, said control device including trip mechanism to release the holding means as to the openable member, mechanism for re-setting the released holding means including a solenoid, and a switch in said housing to control said solenoid, said holding means being operable to release the member for opening only when the latter mechanism has re-set the control device.

CHARLES F. MEILINK.
